(57) **CLAIM**

The ornamental design for a motor scooter and/or toy replica thereof, as shown and described.

DESCRIPTION

FIG. 1 is a front perspective view of a motor scooter and/or toy replica thereof showing our new design;

FIG. 2 is a rear perspective view thereof;

FIG. 3 is a bottom perspective view thereof;

FIG. 4 is a left side elevational view thereof;

FIG. 5 is a right side elevational view thereof;

FIG. 6 is a front elevational view thereof;

FIG. 7 is a rear elevational plan view thereof;

FIG. 8 is a top plan view thereof; and,

FIG. 9 is a bottom plan view thereof.

Stippling and contour lines shown in FIGS. 1-9 are intended to represent three-dimensional contours of the design, and are not intended to indicate surface decoration.

The broken lines in the drawings illustrate portions of the motor scooter and/or toy replica thereof that forms no part of the claimed design.
